UNITED STATES PATENT OFFICE

WALDEMAR L. LINDGREN, OF WAUKEGAN, ILLINOIS, ASSIGNOR OF ONE-HALF TO
JOHN E. ERICSSON, OF CHICAGO, ILLINOIS

DISHWASHING MACHINE

Application filed August 14, 1928. Serial No. 299,486.

My invention is concerned with dish washers, and is designed to produce an extremely simple portable device intended primarily for domestic use and dispensing with all pumping mechanism, and whereby dishes can be quickly and efficiently washed, with a minimum expenditure of energy, as nothing but fresh water is applied at any time to the dishes.

10 My invention is further concerned with a simple device of the class described in which, by simply connecting it to a hot-water faucet and operating the carrier, the dishes placed on the receiving end are first sprayed with 15 soapy water and then sprayed with hot rinsing water to clean off the soap before they are discharged from the carrier.

To illustrate my invention, I annex hereto two sheets of drawings, in which the same 20 reference characters are used to designate identical parts in all the figures, of which,—

Fig. 1 is a side elevation;

Fig. 2 is a sectional view, on a slightly larger scale, on the line 2—2 of Fig. 1;

25 Fig. 3 is a central, longitudinal section;

Fig. 4 is a fragmentary detail, showing the construction of a skeleton carrier;

Fig. 5 is a view in horizontal section on the line 5—5 of Fig. 3; and

30 Figs. 6 and 7 are perspective views further illustrating the construction of the soap box.

In carrying out my invention, I preferably employ a frame made up of two substantially symmetrical side castings 10 having the feet 35 11 adapted to rest on the bottom of a sink, and these are connected at their ends by a pair of castings 12 having triangular sides and a horizontal top plate, which preferably has a covering 12^a of rubber. Journaled in 40 suitable bearings in one end of the side frames is a shaft 13 having secured thereon, just inside of the frame members, the sprocket wheels 14, which are adapted to co-operate with the rods 15, best seen in Fig. 4, which 45 are connected at their ends by the links 16 so as to form an endless skeleton carrier which may be supported on its upper run by the ribs 17 projecting inwardly from the sides of the frame members 10. At the other end of 50 the frame, I provide a shaft 18, having se-

cured thereon a corresponding pair of sprocket wheels 19, although it will be understood that I might employ an equivalent construction. With the construction thus far described, it will be obvious that I have 55 a skeleton carrier on one end of which the dishes to be washed may be placed, so that by turning the handle 20 secured to the shaft 13, or by otherwise rotating the shaft, the dishes may be advanced to the other end of 60 the apparatus, to be washed by the devices hereinafter described.

For this purpose, I provide a connection 21, adapted to be quickly secured to the hot-water faucet of a sink, or some other suitable source of a water supply under a head, and having the short pipe 22 connected by the elbow 23 with the short pipe 24 connected to the T 25, the opposite end of which has secured therein the pipe 26 leading to the 70 combined soap and spray receptacle 27, to be more fully described hereinafter. The T 25 also has extending upwardly therefrom the pipe 28, which is preferably supported by the bracket 29 secured to the adjacent side 75 casting 10 of the framework, and the upper end of the pipe 28 is connected by the elbow 30 with the pipe 31 connected at its other end to a combined soap and spray receptacle 27^a, which is like the receptacle 27 except that it sprays downwardly instead of upwardly. The T 25 has a third horizontal pipe 32 extending alongside the framework and connected by the elbow 33 with the T 34, which has its horizontal outlet connected to the pipe 35, extending inwardly through the adjacent side casting 10 and terminating in the spray member 36 to be more fully described. The T 34 also carries the upwardly extending pipe 37, which is connected at its 90 upper end by the elbow 38 with the horizontal pipe 39 having secured at its inner end the spray receptacle 36^a, similar to the receptacle 36, except that it sprays downwardly instead of upwardly. The inner walls 95 of the frame pieces 10 are preferably lined by the sheet-metal plates 40, seen in section in Fig. 2, and I preferably employ the generally-rectangular, sheet-metal cover 42 open at its ends, and strengthened there by the in- 100

verted U-shaped wires 43, the cover containing openings at the upper end to accommodate the spray portion of the members 27^a and 36^a. This cover is preferably detachably secured to the upper edges of the frames 10 by the ears 44 and screws 45, as shown in Fig. 1.

The spray members 36 and 36^a have their top and bottom portions, respectively, formed semicylindrically in longitudinal cross-section, i. e., in the direction of the length of the machine, and curved in transverse cross-section, as will be seen in the similar bottoms of the combined soap and spray receptacles 27 and 27^a. The result of this shaping of the perforated bottoms is to deliver a spray of water that extends substantially to the sides of the machine, striking on the dishes that may be carried, as well as on all parts of the carrier and frame, so that the entire machine is self-cleansing, as it were, as it is being constantly washed by fresh hot water, and any dirt detached from the dishes is washed off of the machine and into the bottom of the sink, whence it flows to the drain.

The combined soap and spray members 27 and 27^a have the same spraying perforations, but have in addition the generally-rectangular, central cavity 46 that has an opening in its outer end, which is adapted to be closed by the integral flanged end 47 of the sheet-metal soap-box 48 adapted to fit in but be spaced away from the inner walls of the rectangular portion of the receptacles 27 and 27^a. The four sides of the soap holder or box 48 may be formed of a single piece of sheet-metal, one end being closed by the flanged end 47, as previously described, while the other end is closed by the removable sheet-metal strip 49, adapted to fit in said otherwise open end, and to have its ends turned inward and provided with lugs 50 adapted to fit in the two opposed apertures 51 formed in the sides of the adjacent end of the soap box 48. This piece 49, being formed of sheet-metal, has sufficient elasticity so that it can be sprung into place with its ears 50 entering the recesses 51. The four sides of the soap box are provided along each angle with a row of rather large perforations 52, and the operation of this novel combined soap receptacle and spray is to cause the hot water flowing from the pipes 26 and 31 against the bottom and top, respectively, of the soap boxes 48 to enter the perforations 52 and flow along the sides of the cake of soap 53 therein, with the result that the sides of the cake are worn away first, and eventually the central part will be worn away by the continued flow of the water therein. I have found, experimentally, that if the water is admitted against the center of the cake of soap, the central portion alone is worn away and the resulting operation is defective as compared with the use of the structure here-

in shown. I have also found, experimentally, that if the water is taken into the piping at the level of the top of the machine, most of it sprays out through the upper spray members 27^a and 36^a, and there is not sufficient pressure in the lower members 27 and 36, but by taking the water from the lower level, a sufficient spray is secured from the members 27 and 36, and that gravity aids the reduced pressure of the upper members 27^a and 36^a.

The operation of my improved apparatus will be readily apparent. Assuming that the dishes are placed on the left-hand end plate or table 12 and thence shoved on to the skeleton carrier operated by turning the handle 20, they will be carried as slowly as may be desired, first beneath the spray of hot suds, and then beneath the spray of hot rinsing water, so that they will emerge at the other end and be discharged on to the other table 12 clean.

To hold the soap box 48 firmly, but readily detachable, in the receptacles 27 and 27^a, I provide on one side of said receptacles the pair of ears 54, between which is pivoted the link 55 in turn pivoted to the link 56, which in turn is pivoted to the link 57 having the hook end 58 adapted to catch over the pin 59 extending between the ears 60 opposed to the ears 54. A thumb screw 61 is threaded through the center of the link 56 and engages the center of the outer face of the end piece 47, which can thus be screwed as tightly against the adjacent end of the receptacle 27 or 27^a, as the case may be, as may be desired. A strip of rubber packing 62 is preferably interposed between the flanged end of the piece 47 and the adjacent surface of the receptacle 27 or 27^a, to make the joint water-tight.

When the cake of soap is used up, by loosening the screw 61, the soap box can be removed and the end 49 taken out, and a fresh cake of soap put in place. In order to give access to the receptacle 27, I provide the oval opening 63 in the frame 10, and a corresponding opening in the lining 40, this opening normally being closed by the outer cover plate 64 fitting thereover, as seen in Fig. 1.

While I have herein shown and described a novel soap container for use in my dishwasher, I do not herein claim said soap container, but reserve the same for a divisional application.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a dish-washing apparatus, the com-

bination with a bottomless framework of a size adapted to be placed in a kitchen sink, of an endless skeleton carrier mounted thereon to carry the dishes placed on the horizontal upper run from the receiving to the discharge end of the machine, perforated spray members extending transversely of the carrier above and beneath said horizontal upper run, means for connecting said spray members to a faucet in the sink, and means for operating said carrier, the organization being such that the dishes on the carrier and the carrier itself and the adjacent framework are washed, and any dirt washed off of them is carried vertically downward directly to the bottom of the sink.

2. In a portable dish-washing machine, the combination with a bottomless frame, of a skeleton carrier mounted therein, spraying means having spraying orifices for soapy water adjacent the receiving end of the machine, spraying means for clear water adjacent the discharging end of the machine, connections from said spraying means to a source of hot-water supply having a head, so that hot water can flow directly to both of said spraying means by its own head, and a receptacle adapted to contain soap intermediate the source of supply and the spray orifices of the first spraying means, so that the clear hot water flowing to said soapy-water spraying means through said receptacle dissolves some of the soap, so that as the dishes are carried through the machine they are first sprayed with clean soapy water and then with clean clear water, all the water passing through the spraying means being discharged immediately from the machine, so that nothing but clean soapy water and clean clear water is sprayed on the dishes, said clean soapy water and clean clear water being sprayed simultaneously, but on different parts of the carrier.

3. In a portable dish-washing machine, the combination with a bottomless frame, of a skeleton carrier mounted therein, a pair of spraying means having spraying orifices for soapy water adjacent the receiving end of the machine, one mounted above the carrier and the other below it, a pair of spraying means having spraying orifices for clear water adjacent the discharging end of the machine and similarly located relative to the carrier, connections from said spraying means to a source of hot-water supply having a head, so that hot water can flow directly to both pairs of spraying means by its own head, and a receptacle adapted to contain soap intermediate the source of supply and the spray orifices of each of said soapy-water spraying means, so that the clean hot water flowing to said soapy-water spraying means through said receptacles dissolves some of the soap, so that as the dishes are carried through the machine they are first sprayed from above

and below with clean soapy water and then with clean clear water, all the water passing through the spraying means being discharged immediately from the machine, so that nothing but clean soapy water and clean clear water is sprayed on the dishes, said clean soapy water and clean clear water being sprayed simultaneously, but on different parts of the carrier.

In witness whereof, I have hereunto set my hand this 4th day of August, 1928.

WALDEMAR L. LINDGREN.
